PRESSURE OPERATED ELECTRIC CIRCUIT CONTROLLER

Application filed January 4, 1929. Serial No. 330,312.

This invention relates to systems of electric circuit control in which the circuit is opened and closed by a main switch operated by a relay device, which in turn is governed by a primary switch. Its object in this regard is to provide in a primary switch for the purpose indicated, adjustable pressure operated means for causing the relay controlling circuits to be opened and closed at definitely established limits of a pressure or temperature differential. That is, my object is to enable the differential between the pressures or temperatures at which the main switch is respectively opened and closed to be set, adjusted and maintained at accurate points in a range of temperatures or pressures.

In another phase the invention relates to features of construction of a pressure operated switch with the object of improving the same in particulars which are described in the following specification.

These and other objects and the principles of which the invention consists can be best set forth in connection with a detailed description of one embodiment of the invention. Such an embodiment is illustrated in the accompanying drawings, in which,—

Fig. 1 is a front elevation partly broken away of such illustrated switch;

Fig. 2 is a rear elevation of the switch;

Fig. 3 is a front elevation of the switch with the cover, crystal and dial removed, showing the interior parts;

Fig. 4 is a view similar to Fig. 3, but representing the adjustable parts in a different position;

Fig. 5 is a cross section on line 5—5 of Fig. 3;

Fig. 6 is a cross section similar to Fig. 5, but showing a different form of switch containing certain features of the invention which are claimed herein;

Fig. 7 is a wiring diagram of a circuit con-

trolling system, including a relay switch, in which my control invention is used.

Like reference characters designate the same parts wherever they occur in all the figures.

Referring first to the diagram for illustration of the use to which one of the embodiments of my invention herein illustrated is intended, *a* represents an electrical load which may be a heating coil or other heating unit, an electric motor, a set of electric lights, or any other contrivance operated by electric current under circumstances of use which require the current flow to be turned on and off from time to time. *b* represents generically a relay switch device, which may be an apparatus of any character adapted to close and open the circuit in which the load is included, under control of different primary electric circuits, current flow through one of which causes the relay switch to be closed, and flow through the other of which causes the relay switch to be opened. 1 is the controller in which particularly the present invention is embodied, the same being connected with the relay device by three wires, herein designated as C, H and L, respectively. C is the center wire of the three and is in connection with the source of current, whatever that may be, which delivers current to the load circuit. When the circuit is completed between wires C and L by the controller 1, the relay is operated to complete the circuit through the load, and when connection between C and L is broken, and a connection is made from C to H, the relay switch in the circuit of the load is opened. That is, these results occur when the conducting elements of the circuit and of the controller are arranged and connected as shown in the present drawings. It is obvious, however, that the connections for H and L may be reversed, or the relay may be reversely connected in the load circuit, in either of which cases results opposite to those just described will occur.

Describing now the controller instrument shown in detail in Figs. 1-5, the same comprises a case having a rear wall 2, side walls 3, a detachable cover 4 having a flange 4a adapted to embrace the side walls, and a crystal 5 confined between the forward edge of the side walls and the cover. The latter may be of opaque material having a window 6 suitably located to expose to view a scale 7, and an index pointer or hand 8 which cooperates with the scale.

As a convenient and preferred measure of construction, the back may be made as a casting having a peripheral flange 9 rabbeted at its edge to receive the side walls 3; such side walls may be made of a section of seamless tubing of suitable diameter and length, and the cover may be made of sheet metal with its flange 4a drawn or spun at its circumference. The dial 7 is supported by being fastened to two, or permissibly a greater number of, lugs 10 which are partially severed from the side walls by cuts extending inwardly from the forward edge thereof, and bent toward the interior of the case.

A base plate 11 of insulating material is mounted on the back of the case, in an adjustable manner presently described, and on this plate are fastened bars 12 and 13 of conducting material and a pivot 14 of a lever 15, which likewise is made of conducting material. The bar 12 is connected by a conductor 16 with a binding post 17 to which also the wire H is connected. Said bar contains a socket 18 in which is a sliding contact piece 19 under pressure of a spring, shown in Fig. 5, which tends to expel it from the socket to the limit permitted by a stop 20 on the stem of the contact piece. The bar 13 is connected by an electrical conductor 21 with the binding post 22 to which the wire L is connected. In this bar is a stationary contact 23 which projects toward the contact 19 and is secured by a set screw 24 in a manner permitting it to be adjusted endwise so that it will protrude more or less. The lever 15 is connected by means of a conductor 25 with the binding post 26 to which the wire C is likewise connected. This lever extends between the contacts 19 and 23 and has opposite faces adapted to engage with these contacts respectively. The distance between such faces, the distance to which the sliding contact 19 projects, and the range of adjustment of the contact 23 have such values that the lever may be caused to leave either contact when coming into engagement with the other, but the excess of space between the contacts may be diminished to the vanishing point.

A curved spring tube 27 of flattened cross section, closed at one end and open at its other end, is secured to a socket 28 with its open end entering the socket and in communication with the passage 29 therein. Such socket passes through the side wall of the

casing and is provided with flanges which are secured thereto by screws. This spring tube corresponds to the familiar Bourdon spring of a pressure or vacuum gauge, and the socket to the usual socket of such gauges. To the socket is connected a pipe 30 which conducts fluid, whether liquid, gas or vapor, from any source whatsoever.

The spring tube is designed to shift the switch lever 15 when flexed by variations in its contained fluid pressure, and to that end a lost motion connection is provided consisting of a bar 31 carried by the spring tube, and a loop or frame 32, through which said bar extends; the loop or frame being secured on the end of a post 33 which in turn is rigidly secured to an arm 34 projecting forwardly from the lever 15. By this means, distortion of the spring tube caused by increasing pressure raises the switch arm into contact with the sliding contact 19, withdrawing it first from the fixed contact 23, and the sliding contact is adapted to yield in case the pressure continues to rise, and the spring tube to be further distorted after engagement has been effected. Relaxation of the spring tube with decreasing pressure allows the switch lever to return into engagement with the fixed contact, being actuated to that end by a spring 35, and by gravity also when the controller is placed in an upright position. The spring 35 is here shown as made of a length of spring wire coiled about a stud 36, which holds it in position, and pressing at one end on the switch lever at a point remote from the pivot of the latter, while its other end bears on the hub portion of the lever which serves as an abutment.

The bar 31 previously mentioned extends approximately parallel to a portion of the spring tube 27. It is connected to the spring tube by arms 37 and 38 at its opposite ends which are soldered or otherwise suitably fastened to the spring tube. The arms 37 and 38 may be conveniently made from the opposite ends of a single, suitably bent, piece of wire, the central part of which is passed through the tubular bar 31, which is a sleeve or section of tubing made of rubber or other suitable insulating material. However, an equivalent structure may be constructed otherwise as to its details. Important features, however, are that the bar has substantial length, is spaced away from the spring tube toward the center about which the tube is curved, and has substantially less width than the space enclosed by the loop or frame 32, as well as that it extends generally parallel to that part of the spring tube beside which it lies. These characteristics permit lost motion between the spring tube and the switch arm and likewise permit an adjustment whereby the switch will be operated on a greater or less pressure differential.

To permit of the adjustment last referred

to, the base plate 12 is connected to a pivot 39 which passes through a hole in the back of the case and has a flange 40 bearing against the inner surface of the back wall, to which the base plate 11 is secured. An arm 41 on the outside of the back wall is secured to the protruding end of the pivot, the latter preferably having a non-circular outline and the arm 41 having a hub with a hole complementary thereto, which is held thereon by the overlying head of a screw 42 threaded into the pivot stud. The adjusting arm 41 has a widened slotted part 43 through which protrudes a stud 44, mounted on the back of the case and carrying a clamp nut 45. The arm also has a handle or finger piece 46 extending beyond the circumference of the case. By means of this handle the entire switch (comprising the base plate, contacts and switch lever, with their electrical connections) may be rotated as a unit about the axis of the case within the limits of the slot in the adjusting arm. As the spring tube 27 is curved about a center near the axis of the case, these adjustments shift the inner and outer members of the loop 32 in paths approximately concentric with the tube. The bar 31, however, is not concentric with the axis of adjustment but is so inclined that, when the switch is in one extreme position, that illustrated in Figs. 1, 2, 3 and 5, the lost motion between the bar and the upper member of the frame is a maximum, while in the other extreme adjustment, shown in Fig. 4, the lost motion is a minimum. In the latter position, moreover, the frame is brought nearer to the end of the spring tube which has the greatest amplitude of movement when distorted by pressure.

The same adjustments likewise shift the pointer or index 8, and for that purpose a pair of arms or jaws 47 are connected to the index and receive between them a rod or finger 48 which is mounted on the switch base 11. As a convenient detail of construction, the jaws or arms 47 are made as integral projections from the opposite edges of a U-shaped bar 49, the ends of which are parallel to one another and are apertured and placed upon a fixed stud 50 which is mounted in a lug 51 on the socket 28, and serves as a pivot. The index 8 is secured to the forward end or leg of this U-shaped bar. This construction enables the U-shaped bar and the jaws 47 to be formed out of a single blank of sheet metal.

The foregoing description is given with reference to the normal or relaxed condition of the spring tube, which is the condition shown in the drawings. The action of a Bourdon spring, of which the tube 27 is one example, when distorted by increasing internal pressure, is to approach a straight line, and that part of the tube to which the bar 31 is attached moves in a direction conforming in

a general way to the path in which the frame 32 is constrained by the pivot 14 to move. The first part of this movement has no effect on the switch, when the adjustment is such that any space is left between bar 31 and the top of loop 32, but after the bar 31 has crossed the space provided for lost motion, it engages the upper member of the loop and withdraws the switch lever from contact 23, shortly afterward bringing it into contact with the other contact 19. By means of the adjusting arm 41, the preliminary lost motion may be varied between zero and any desired maximum; while by adjustment of the fixed contact 23 the movement of the switch lever after leaving one contact and before reaching the other may be made as great or little as desired, some lost motion being necessary in all cases, however.

In the foregoing description it has been assumed that the shifting of the switch occurs between atmospheric pressure and pressures higher than atmospheric. However, the same principles are applicable to situations in which the action is controlled by vacuum conditions. The same Bourdon spring, or other pressure responsive agent, which is displaceable in one direction from a condition of rest by internal pressures greater than atmospheric, is displaceable in the opposite direction by atmospheric pressure when a partial vacuum is created in its interior. A bare reversal of the contacts 19 and 23 is sufficient to make the controller hereinbefore described operate under vacuum conditions; and indeed it may be so operated even without such reversal by adjustment or arrangement of the parts in such fashion that the switch lever engages the contact 19 and is separated from the contact 23 when the Bourdon spring is in the normal position of rest.

A somewhat different construction organized for vacuum operation is shown in Fig. 6. In this case the normally stationary contact 23a is carried by a bar 52 projecting from the base 11a, and the circuit is closed and opened by movement of a contact 19a into and out of engagement with the contact 23. The movable contact 19a is virtually a reversed duplicate of the contact 19 except that in place of the stop collar 20, a frame 53 is secured to its protruding shank, and its guide is offset so that it may be embraced by such frame. The top bar of the frame lies beneath the operating bar 31 (when the controller is in the position shown in the drawings) so that contraction of the Bourdon spring by vacuum causes the movable contact to be withdrawn from the fixed contact. In other respects, including the capacity for adjustment of the switch and the effects obtainable thereby, this form of controller is essentially like that previously described.

Inasmuch as the controller connected in

the three-wire circuits first described accomplishes its ultimate effect indirectly through a relay, it does not transmit a heavy current at any time, or any current longer than momentarily. When its movable switch arm engages either contact, current flows only long enough to actuate the relay so as to open or close the main switch, as the case may be, and the relay may be operated by a current of small magnitude, and after being operated breaks the circuit. That is, various relay devices known to the art do so, and my controller is designed to cooperate with such relay devices. When used in such conditions there is no sparking or tendency to create an electric arc when the switch arm is withdrawn from either contact. The form of switch shown in Fig. 6, however, is adapted to carry a heavy current continuously and for that purpose its contacts are large and massive, having plane faces which are perpendicular to the line in which the contact 19a is constrained by its guide to move. Thus the contact members have a multitude of points in contact when they are brought together, through which current may flow, and such points are simultaneously and equally separated when the movable contact is withdrawn from the other; wherefore the heating effect at the contact area is small even though a large current is passed, and sparking upon separation is largely prevented.

Controllers embodying the principles of this invention are usable in many situations for a great variety of purposes, whether for the purpose of generating heat, mechanical power, or light. The actuating force in the controller here illustrated is pressure, which may be created in a fluid by heat or by mechanical power. If control by temperature differential is desired, the pipe or tube 30 may be connected with a closed bulb or the like containing the fluid, and if the limiting temperatures are both low, the fluid used may be a volatile fluid having a low boiling point. Or the pressure may be transmitted by expansion or contraction, without vaporization, of a liquid; or by like actions of a fixed gas.

The Bourdon spring here shown is merely one illustration of a pressure responsive element. Other pressure responsive devices are known and may be applied to the purposes of the invention as equivalents of the specific one shown. Since pressure developed by heat is a function of the temperature, the pressure responsive element when used under temperature control is likewise a temperature responsive element, for which various other equivalent temperature responsive devices of specifically different construction may be used within the scope of the invention. Therefore the term "temperature responsive element" is used in a generic sense to include all equivalent devices which are distorted by temperature differences, whether by direct

effect on the element or indirectly through conversion into pressure differences, or are capable of being so distorted.

What I claim and desire to secure by Letters Patent is:

1. A circuit controller comprising a curved temperature responsive element, an electric switch mounted for angular adjustment about an axis nearly coaxial with the curvature of said element, a bar carried by said element and extending generally lengthwise thereof near the end thereof which has the greatest movement when distorted in response to temperature changes, a frame connected to the circuit closing and opening member of said switch having a portion crossing said bar adapted to be engaged and moved by the latter when the temperature responsive element is distorted. 70

2. A circuit controller comprising a curved temperature responsive element, an electric switch mounted for angular adjustment about an axis near the center of curvature of said element, a bar carried by said element near the end thereof which has the greatest movement when distorted in response to temperature changes, a frame connected to the circuit closing and opening member of said switch having a portion crossing said bar adapted to be engaged and moved by the latter when the temperature responsive element is distorted, said bar occupying a position inclined to the path in which the said frame portion is moved by adjustment of the switch, whereby such adjustment causes a distance of varying width to exist between the bar and frame permitting greater or less movement of the temperature responsive element to occur before the switch member is shifted. 80

3. In a controller of the character described, an angularly adjustable switch, an index pivoted independently of the switch, and a projection on said switch engaging said index at one side of its pivot and arranged to move the index angularly when the switch is so adjusted. 90

4. In a controller of the character described, an adjustable movable switch, a bar having upturned parallel apertured ends, a stationary pivot occupying the apertures therein and about which the bar is oscillatable, said bar having also arms or jaws extending side by side from its opposite edges, an index secured to one of the upturned ends of the bar and a projection from the switch entering between said jaws adapted to move the same and the index about said pivot when the switch is adjusted. 100

5. A circuit controller comprising a casing, a switch base mounted in said casing with provision for rotative adjustment movement, separated electrical contacts and a pivoted switch lever between them, mounted on said base and insulated from one an- 110

other, separate conductors leading respectively from said contacts and switch lever and adapted to be separately connected with the conductors of a three-wire electrical system, a curved temperature responsive element mounted in said case substantially coaxial with the switch base, being secured at one end and free at the other, a bar carried by said element near the free end of said element and extending generally longitudinally thereof, and a frame connected to said switch lever and having a member extending across said bar and the path of movement thereof.

15 In testimony whereof I have affixed my signature.

EMERY J. DASHNER.
